11 Claims. (Cl. 343—121)

This invention relates to a direction finder, and more particularly to a direction finder capable of developing a visual indication of the direction of an intercepted electromagnetic wave signal.

An object of the instant invention is the advancement, generally, of the art of radio direction finding.

Another object of the present invention is to provide a directly visual type direction finder characterized by a high sensitivity and degree of accuracy.

Said objects and other objects have been attained by a direction finder comprising a receiving section which produces a time-division signal composed of four output voltages having divers phase relations relative to one another, said output voltages resulting from a combination of two pairs of aerials which are physically arranged on lines perpendicular to each other; an amplifier which amplifies the time-division signal; a switching device which separates the signal into direct current voltages each having a value equal to the peak value of each of said output voltages; a device which combines the direct current voltages into two pairs of output voltages capable of giving direction indication; a device which produces two alternating current voltages, each being proportional to the difference between the amplitudes of each pair of combined direct current voltages; a device which applies the alternating current voltages to the horizontal and vertical deflection plates of a cathode ray tube after amplification thereof; a device which applies a voltage having a frequency equal to that of the alternating current voltage to the intensity grid of the cathode ray tube thereby to obtain a trace of a unidirectional indication.

An ordinary electric direction finder of direct visual system heretofore in use has a low sensitivity, because of adoption of the minimum sensitivity method. Furthermore, the direction finder of time-division system heretofore in use is variant and unstable in its direction indication and is apt to be accompanied with error due to fading of the incoming signal, etc.

The direction finder in the present invention, contrary to the aforesaid defects of the direction finder heretofore in use, works with very high sensitivity and stability because peak values of time division signals are stored in the time constant circuits and the noise effect is cancelled. Furthermore, the present invention has a characteristic that reading of direction is made easy and correct, because indication of direction is established so as to be acute.

The novel features of the present invention are set forth with particularity in the appended claims. The invention, however, both as to its manner of construction and operation together with further objects and advantages, may be best understood by reference to the following detailed description taken in connection with the accompanying drawings, in which the same elements are indicated by the same reference characters throughout the several views, and in which:

Fig. 1 is an electric connection diagram illustrating

one embodiment of the basic principle of the present invention.

Fig. 2 is a diagram showing the figure on the fluorescent surface of the cathode-ray tube illustrating the basic principle of the present invention.

Figs. 3(a), 3(b), 3(c), 3(d) and 3(e), respectively, show the voltage wave forms illustrating the basic principle of the present invention.

Figs. 4, 5, and 6, are electric connection diagrams illustrating the other embodiments of the present invention.

Figs. 7(a), 7(b), 7(c), 7(d), 7(e), 7(f) and 7(g), respectively, show the voltage wave forms illustrating the basic principle of the illustration in Fig. 6.

Fig. 8 is a diagram of a converter to obtain rectangular wave, which is used in Fig. 6.

Fig. 9 is a diagram showing the figure on the fluorescent surface of a cathode-ray tube in Fig. 6.

Referring now to Fig. 1, let it be supposed that A_1 , A_2 , B_1 and B_2 are aerials arranged on the apexes of a regular square as in the arrangement of the well known Adcock aerials. If a radio wave signal comes from the direction which makes an angle of β with A_1A_2 , then the respective outputs of the aerials A_1 , A_2 , B_1 and B_2 will be:

$$\begin{aligned} E_{A1} &= E_0 e^{\frac{j\pi d}{\lambda} \cos \beta} \\ E_{A2} &= E_0 e^{-\frac{j\pi d}{\lambda} \cos \beta} \\ E_{B1} &= E_0 e^{\frac{j\pi d}{\lambda} \sin \beta} \\ E_{B2} &= E_0 e^{-\frac{j\pi d}{\lambda} \sin \beta} \end{aligned} \quad (1)$$

wherein d is the distance between the two aerials of a pair which are confronting each other and λ is the wave length of the impinging radio wave signal. As a practical matter the several voltages are developed across impedances in the aerial connecting wires in the usual manner known in the art. If the outputs of each pair of aerials are, respectively, combined differentially by transformers T_a and T_b , then a combined voltage having a directivity of Figure 8 will be obtained on each secondary winding of said transformers.

$$\begin{aligned} E_{AD} &\propto E_{A1} - E_{A2} = j2E_0 \sin\left(\frac{\pi d}{\lambda} \cos \beta\right) \\ -E_{AD} &\propto E_{A2} - E_{A1} = -j2E_0 \sin\left(\frac{\pi d}{\lambda} \cos \beta\right) \\ E_{BD} &\propto E_{B1} - E_{B2} = j2E_0 \sin\left(\frac{\pi d}{\lambda} \sin \beta\right) \\ -E_{BD} &\propto E_{B2} - E_{B1} = -j2E_0 \sin\left(\frac{\pi d}{\lambda} \sin \beta\right) \end{aligned} \quad (2)$$

These combined voltages are successively supplied to the amplifier A_{p1} through one of the exchange devices S_1 , S_2 , S_3 , and S_4 of a switching device S per every one quarter period by switching said exchange devices in the sequence of S_1 , S_2 , S_3 , and S_4 , said device S being controlled by the output of a four-phase generator O_c .

On the other hand, the resultant voltage E_s at a terminal of the grounded coil inserted in the circuit of four aerials will be as follows:

$$\begin{aligned} E_s &= E_{A1} + E_{A2} + E_{B1} + E_{B2} \\ &= 2E_0 \left\{ \cos\left(\frac{\pi d}{\lambda} \cos \beta\right) + \cos\left(\frac{\pi d}{\lambda} \sin \beta\right) \right\} \end{aligned} \quad (3)$$

and it has a phase difference of 90° with E_{AD} and E_{BD} . This resultant voltage E_s is supplied to a transformer T ,

and then converted to a voltage having the same phase as the phases of the voltages E_{AD} and E_{BD} by shifting the phase by 90° by a phase shifter Φ . This phase shifted voltage is superimposed on each combined voltage and is supplied to the amplifier A_{P1} . The same result will be obtained by another system, in which the same radio wave is received by another aerial and the output of said aerial is amplified after being properly shifted to have the same phase as the phases of the voltages E_{AD} and E_{BD} , and then applied to amplifier A_{P1} . Then, four kinds of the following voltages employed for determining the bearing are successively impressed on the amplifier A_{P1} for every one quarter period of the controlling voltage of the generator O_c .

$$\begin{aligned} E_1 &= jE_s + E_{AD} \\ E_2 &= jE_s + E_{BD} \\ E_3 &= jE_s - E_{AD} \\ E_4 &= jE_s - E_{BD} \end{aligned} \quad (4)$$

The output of the amplifier A_{P1} is separated into voltages E_{a1} , E_{b1} , E_{a2} and E_{b2} , which are, respectively, proportional to E_1 , E_2 , E_3 and E_4 , by means of a switching device S_a the operation of which is controlled by the output of the four phase generator O_c as in the case of the switching device S .

The voltages E_1 , E_2 , E_3 and E_4 are, respectively, supplied to the peak value rectifier circuits D_1 , D_2 , D_3 and D_4 through one of the exchange devices S_{a1} , S_{a2} , S_{a3} , and S_{a4} of a switching device S_a by sequential switching in the order of S_{a1} , S_{a2} , S_{a3} , and S_{a4} , whereby the direct current voltages proportional to the separated alternating current voltages E_1 , E_2 , E_3 and E_4 are taken out of the rectifier circuits D_1 , D_2 , D_3 , and D_4 . The direct current voltages taken out as hereinbefore described are combined in two pairs and then are, respectively, supplied to the converters F_1 and F_2 of the indicating device, to convert their waves into such sine waves as shown in Fig. 2(b) and Fig. 2(d), which are, respectively, proportional to the difference between the voltages E_{a1} and E_{a2} and between E_{b1} and E_{b2} . The output voltages of converters F_1 and F_2 are respectively made as the north-south and east-west components and these components are supplied to the vertical and horizontal deflection circuits of a cathode-ray tube B to indicate a linear figure on the fluorescent surface. On the other hand, a voltage, which is produced by properly shifting a part of the output of the generator O_c by a phase shifter Φ , and by rectifying said shifted voltage through the rectifier D_5 , the wave of said voltage being shown by the full line of Fig. 2(e), is supplied to the intensity control grid of the cathode-ray tube B to make the half period of the linear figure blank thereby to obtain an unidirectional indication of the bearing of the radio wave as shown in Fig. 3. The principle of operation of the switching device S_a etc. will be explained in detail in Fig. 5 etc.

The signals E_{AD} (or E_{BD}) and E_s , which are supplied to the amplifier A_{P1} ought to have a phase difference of 90° relative to each other, but generally speaking, there are some phase shifts owing to the mutual coupling of the aerials. Now, let it be assumed that the component of the voltage E_s , the phase of said component being same with the phase of the voltage E_{AD} (or E_{BD}), is E_x and the other component of said voltage E_s , the phase of said component being orthogonal to the former component, is E_R , then E_s is expressed by the following formula.

$$E_s = E_R + jE_x \quad (5)$$

When a linear detector is employed as the rectifier circuits D_1 , D_2 , D_3 and D_4 , the following indication angle θ of a cathode-ray tube B is obtained by substituting the Formula 5 for Formula 4.

$$\theta = \tan^{-1} \frac{\{(E_R - jE_{BD})^2 + E_x^2\}^{1/2} - \{(E_R + jE_{BD})^2 + E_x^2\}^{1/2}}{\{(E_R - jE_{AD})^2 + E_x^2\}^{1/2} - \{(E_R + jE_{AD})^2 + E_x^2\}^{1/2}} \quad (6)$$

Furthermore, in case

$$|E_R| \geq |E_{AD}|, |E_R| \geq |E_{BD}| \quad (7)$$

the indication angle θ becomes the value shown in the following Formula 8, without relation to the magnitude of E_x , whereby the direction corresponding to β can be indicated.

$$\begin{aligned} -j2E_{BD} &= \sin \left(\frac{\pi d}{\lambda} \sin \beta \right) \\ \theta &= \tan^{-1} \frac{-j2E_{BD}}{-j2E_{AD}} = \beta \end{aligned} \quad (8)$$

Moreover, if square law detectors are used as rectifier circuits D_1 , D_2 , D_3 and D_4 , it will become as follows:

$$\theta = \tan^{-1} \frac{-j4E_R E_{BD}}{-j4E_R E_{AD}} = \beta \quad (9)$$

If only the condition $E_R > 0$ is satisfied, the angle θ may be more approximated to β even if the condition in Formula 7 is not satisfied. Moreover, when square law amplification characteristic is given to an amplifier A_{P1} , instead of employing square law detectors as the circuits D_1 , D_2 , D_3 and D_4 , the same result will be obtained.

The hereinbefore disclosed system relates to the case, in which Adcock aerials are used but a linear figure such as described above can also be obtained by using loop aerials and a vertical aerial which are located at right angles to each other.

As a means for combining the outputs of four aerials, besides the above-mentioned method, the following method may be used. Namely, referring to Fig. 4, aerials A_1 , A_2 , B_1 and B_2 are arranged in the same way as Fig. 1. The output voltages E_{A1} , E_{A2} , E_{B1} and E_{B2} of said aerials are, respectively, shown in Formula 1. If the phases of said output voltages are shifted by a phase shifter P_1 by a certain angle

$$\Phi \left(\frac{2\pi d}{\lambda} < \Phi < \pi \right)$$

each of said voltages will become as shown in the following Formula 10.

$$\begin{aligned} e_{A1} &= E_0 e^{-j\Phi} e^{\frac{j\pi d}{\lambda}} \cos \beta \\ e_{A2} &= E_0 e^{-j\Phi} e^{-\frac{j\pi d}{\lambda}} \cos \beta \\ e_{B1} &= E_0 e^{+j\Phi} e^{\frac{j\pi d}{\lambda}} \sin \beta \\ e_{B2} &= E_0 e^{+j\Phi} e^{-\frac{j\pi d}{\lambda}} \sin \beta \end{aligned} \quad (10)$$

When the voltages whose phases are shifted and the voltages having shifted phases and the voltages having unshifted phases are combined differentially, the following combined outputs for determining the direction are obtained at points a_1 , a_2 , b_1 and b_2 by using Formulas 1 and 10.

$$\begin{aligned} e_{a1} &= j2E_0 e^{-\frac{j\Phi}{2}} \sin \left(\frac{\Phi}{2} + \frac{\pi d}{\lambda} \cos \beta \right) \\ e_{a2} &= j2E_0 e^{-\frac{j\Phi}{2}} \sin \left(\frac{\Phi}{2} - \frac{\pi d}{\lambda} \cos \beta \right) \\ e_{b1} &= j2E_0 e^{-\frac{j\Phi}{2}} \sin \left(\frac{\Phi}{2} + \frac{\pi d}{\lambda} \sin \beta \right) \\ e_{b2} &= j2E_0 e^{-\frac{j\Phi}{2}} \sin \left(\frac{\Phi}{2} - \frac{\pi d}{\lambda} \sin \beta \right) \end{aligned} \quad (11)$$

These four kinds of voltages are converted into time division signals in the order of E_{a1} , E_{b1} , E_{a2} and E_{b2} by an electric switching device S which is controlled by the output of O_c . Then, these time division signals are,

after being amplified by a common amplifier A_{p1} , selected in the order of E_{a1} , E_{b1} , E_{a2} and E_{b2} by a switching circuit S_a as described in case of Fig. 1, and then rectified by peak value rectifier circuits D_1 , D_2 , D_3 and D_4 . These rectified voltages are successively supplied to the alternating current converters F_1 and F_2 to obtain sine wave voltages which are, respectively, proportional to the difference between the voltages E_{a1} and E_{a2} and between the voltages E_{b1} and E_{b2} . These sine waves are, respectively, supplied to the vertical and horizontal deflection circuits of the cathode-ray tube B as the south-north and east-west components. Then, the indication angle θ of the cathode-ray tube B will be given by the following Formula 12.

$$\theta = \tan^{-1} \frac{|E_{b1}| - |E_{b2}|}{|E_{a1}| - |E_{a2}|} = \frac{\sin \left(\frac{\pi d}{\lambda} \sin \beta \right)}{\sin \left(\frac{\pi d}{\lambda} \cos \beta \right)} \div \beta \quad (12)$$

Said angle indicates the bearing of the radio wave.

Fig. 5 shows a connection diagram (abridged partly) of one embodiment of the switching device S_a in Figs. 1 and 4. The output voltages which are received by the aerials A_1 , A_2 , B_1 and B_2 and then combined, and converted into time-division outputs at the receiving section R by an electric switching device (not shown) controlled by the generator O_c . The combined outputs obtained alternately from these outputs are supplied to the indication section Y and to the indication section X, and detailed explanation will be made hereunder. Since the sections Y and X are structurally and operationally equivalent, only the indication section Y will be completely described.

The time-division signals are supplied to the rectifier tubes V_1 and V_2 through the condensers C_1 and C_2 . The tubes V_1 and V_2 are so controlled by applying the output voltage of the generator O_c to the grids of said tubes through a phase shifter Φ_r capable of properly shifting the phase of said output voltage and a transformer T_1 and by properly selecting the bias voltage E_c that the tube V_1 is rendered conductive only when the voltage E_{a1} is arriving and the tube V_2 is rendered conductive only when the voltage E_{a2} is arriving. Accordingly, an electric current proportional to the value of E_{a1} flows through the tube V_1 only when the voltage E_{a1} is arriving and charges the condenser C which constitutes a time constant circuit with R. If the time constant CR is made sufficiently large, the charged voltage which is proportional to the peak value of the voltage E_{a1} is kept constant until the next voltage E_{a1} arrives, and is supplied to the suppressor grid of the modulation tube V_3 as a negative direct current voltage. The same applies also to the tube V_2 , so that said tube supplies a negative direct current voltage which is proportional to the value of E_{a2} to the suppressor grid of the modulation tube V_4 .

On the other hand, the alternating current voltage of the generator O_c is supplied to the control grids of the vacuum tubes V_3 and V_4 through a transformer T_2 . Accordingly, the voltages e_{a1} and e_{a2} the amplitudes of which are, respectively, proportional to the voltages E_{a1} and E_{a2} as shown in Fig. 2(a) are generated at the plates of said tubes. These voltages are combined differentially by the transformer T_3 to obtain an alternating current voltage such as shown in Fig. 2(b) by E_a , said last-mentioned voltage being supplied to the vertical deflection circuit of the cathode-ray tube B.

Concurrently, in the amplifier device X, the voltages shown by e_{b1} and e_{b2} in Fig. 2(c) which are proportional to the value of the voltages E_{b1} and E_{b2} are obtained and differentially combined to obtain the alternating current voltages as shown by E_b in Fig. 2(d) in the same way as described in connection with the voltage supplied to the vertical deflection circuit of the cathode-ray oscilloscope, said voltage being supplied to the horizontal deflection circuit of said tube B. Accordingly, such a linear

figure having an angle θ to the axis Y at the original point O as shown in Fig. 3 will be indicated on the fluorescent surface of the cathode-ray tube B. Moreover, the output of the generator O_c is properly shifted in its phase by a phase shifter Φ_2 , rectified by a rectifier tube V_5 and then supplied to the intensity control grid of tube B as a negative voltage for half a period. Consequently, the part of the trace shown by broken line of the linear figure in Fig. 3 is blanked, whereby the bearing of the radio wave is shown by an unidirectional indication. In the above case, for the purpose of obtaining a linear figure on the cathode-ray tube, the alternating current voltages to be supplied to the tubes V_3 , V_4 and V_5 do not necessarily need the output of the generator O_c for switching device 15 and any other alternating current power source may well be used.

As above-mentioned, rectification of a peak value by using a circuit having a large time constant has advantages that the indication of direction is very stable and 20 the bearing of radio wave is correctly indicated even when the radio wave having the same or more communication speed as compared with the switching speed of the above-mentioned direction finder of time division system is to be measured or when the radio wave followed by a rapid fading is to be measured. Moreover, as the set noise contained in the four time-division signals 25 is of the same value, the noise is nearly cancelled by taking the difference between the voltages of each of the pairs after rectification of the peak value. Therefore, a correct direction indication of a radio wave can be obtained by reason of the substantial reduction in the magnitude of the signal-to-noise ratio.

Fig. 6 shows a modification of the system shown in Fig. 5. By this system, in the same manner as the case of Fig. 5, direct current voltages $-e_{a1}$ and $-e_{a2}$ proportional to the voltages E_{a1} and E_{a2} are obtained from the peak value rectification circuit having the time constant CR. However, in the embodiment in Fig. 6 there is a characteristic in the manner to be used for indicating 30 the difference between said voltages on the cathode-ray tube. Namely, the voltages e_{a1} and e_{a2} are changed over alternately as shown in Fig. 7(a), by a switching device S_r such as a vibrator which works by the output of the generator O_c and then are supplied to the control grid of 35 a vacuum tube V_6 . (Instead of a vibrator, other switching devices, vacuum tubes and etc. may well be used.) The operating range of tube V_6 is regulated so that only the linear part of the characteristic $E_g - I_p$ of said tube 40 may be employed as shown in Fig. 8. When said voltages $-e_{a1}$ and $-e_{a2}$, which are changed over alternately as 45 in case of Fig. 7(a), are supplied to the control grid of the tube V_6 , a rectangular output wave voltage is developed like in Fig. 7(b), said wave having an amplitude $e_a = K'(|e_{a1}| - |e_{a2}|) = K(|E_{a1}| - |E_{a2}|)$ and proportional to 50 the difference between the absolute values of said voltages. A condenser C_s is used to suppress the transient 55 phenomenon in the moving period of the tongue of the vibrator S_r .

Then, the rectangular output wave is supplied to a 60 differential circuit which is composed of a condenser C_d and a resistance R_d , the time constant of which circuit being sufficiently small as compared with the half a period of said rectangular wave. At the two terminals of the resistance R_d , a voltage, having the amplitude 65 $2e_a$ and attenuating exponentially from the maximum value as shown in Fig. 7(c) is obtained. This differentiated voltage is amplified to a proper value by an amplifier A_{p2} of a high fidelity, and then is supplied to the vertical deflection circuit of a cathode-ray tube B. Concurrently, at the indication section X, a differentiated voltage 70 is supplied to the horizontal deflection circuit of said tube B by the same process as mentioned above.

That is to say, a rectangular wave voltage having an amplitude e_b as shown in Fig. 7(e), said amplitude being 75 proportional to the difference between the absolute values

of such voltages $-e_{b1}$ and $-e_{b2}$ as shown in Fig. 7(d), is obtained from the voltage obtained by changing alternately the direct current voltages $-e_{b1}$ and $-e_{b2}$ which are, respectively, proportional to the voltages E_{b1} and E_{b2} . Said rectangular wave voltage is so differentiated as to become the voltage having a wave form as shown in Fig. 7(f), which is amplified by an amplifier of a high fidelity. This amplified voltage is supplied to the horizontal deflection circuit of said tube B. Consequently, on the fluorescent surface of said tube B a linear trace is developed which is thick at its original point and is becoming thinner towards its extremity. The angle inclination of said linear figure is determined by $\tan^{-1}(e_b/e_a)$.

As is clear from the wave forms of the voltages supplied to the cathode-ray tube, the attenuation is rapid at the peaked wave part and slow at the basic portion, so that a substantially long time is required until the wave approaches zero, so that the figure on the cathode-ray tube is thin at the end and thick near the original point. Then, when such a blanking voltage as shown in Fig. 7(g) is supplied to the cathode-ray tube, the portion of the trace indicated in broken line of Fig. 9 is blanked and the direction of the incoming radio wave signal can be indicated clearly and unidirectionally similarly to the indication of a compass needle. Moreover, for the production of alternating current voltage to be supplied to the switching device S_r and to the blanking device T, the output of the generator O_c is indispensable, and other alternating current power source such as a commercial power source may be utilized.

While we have described and shown particular embodiments of our invention, it will, of course, be understood that we do not wish to be limited thereto, since many modifications may be made and we, therefore, contemplate by the appended claims to cover all such modifications as fall within the true spirit and scope of our invention.

What is claimed is:

1. A direction finder comprising an antenna system including four independent aerials each of which is positioned at the apex of a square and adapted to concurrently derive a potential signal having a phase correlative to the bearing of an incoming radio wave relative to the respective aerial, circuit means for differentially combining the potential signals derived by each pair of diagonally positioned aerials, circuit means for developing a resultant signal corresponding to the sum of all of said potential signals and for superimposing said resultant signal upon each of said differentially combined potential signals, circuit means for sequentially amplifying and separating each of said differentially combined potential signals subsequent to superimposition of said resultant signal thereon at a predetermined rate, circuit means for developing direct current voltages each of which is proportional to the peak value of one of said amplified and separated potential signals, circuit means for producing a pair of sinusoidal signals, each of which is proportional to the difference between two of said direct current voltages, a cathode ray oscilloscope, circuit means for individually impressing said pair of sinusoidal signals upon the horizontal and vertical deflection plates of said cathode ray oscilloscope thereby developing a linear trace on the screen thereof, and circuit means for impressing upon the intensity control grid of said cathode ray oscilloscope a pulsating unidirectional signal having a period correlative to said predetermined rate thereby to selectively blank a portion of said linear trace on said screen.

2. A direction finder comprising an antenna system including four independent aerials each of which is physically positioned at the apex of a square and adapted to simultaneously derive a potential signal having a phase correlative to the bearing of an incoming electromagnetic wave relative to the respective aerial, transformer means coupled across the diagonal ones of said aerials for de-

veloping differential signals proportional to the potential signals derived by said aerials, amplification circuit means for developing amplified output signals, first switching circuit means coupled to said transformer means for effecting sequential application of said differential signals to said amplification circuit means, transformer means coupled to said antenna system for producing a resultant signal corresponding to the sum of all of said derived potential signals, circuit means for selectively shifting the phase of said resultant signal, circuit means for impressing said resultant signal upon each of said differential signals immediately prior to amplification thereof by said amplification circuit means, second switching circuit means coupled to said amplification circuit means for effecting sequential separation of said amplified output signals, detector circuit means individually coupled to each of said second switching circuit means for developing unidirectional current signals correlative to the respective separated amplified output signals, a pair of converter circuit means each being individually coupled to a unique pair of said detector circuit means for producing a pair of sinusoidal signals each of which is proportional to the difference between the unidirectional current signals developed by said unique pair of detector circuits, a cathode ray oscilloscope, circuit means for individually impressing each of said pair of sinusoidal signals upon the horizontal and vertical deflection circuits of said cathode ray oscilloscope, and thereby develop a linear trace on the screen thereof, and circuit means for impressing upon the intensity control grid of said cathode ray oscilloscope a unidirectional signal for effecting blanking of a portion of said linear trace.

3. In a direction finder according to claim 2 wherein each of said detector circuit means is a linear detector.

4. In a direction finder according to claim 2 wherein each of said detector circuit means is a square law detector.

5. In a direction finder according to claim 2, and including circuit means for effecting synchronous sequential operation of said first and second switching circuit means.

6. In a direction finder according to claim 5 wherein said circuit means comprises a four phase alternating current generator.

7. A circuit for developing an output alternating current signal correlative to the sum of a pair of sequential alternating current input signals comprising an input terminal to which the pair of signals are applied, a pair of capacitors, a common terminal, a pair of triodes the respective cathodes of which are connected to said common terminal and the respective plates of which are individually coupled to said input terminal through one of said capacitors, a first transformer the secondary winding of which is connected between the respective control grids of said triodes, a first fixed bias source interposed between said common terminal and the center of said secondary winding, a phase shifter, an alternating current source coupled to the primary winding of said transformer through said phase shifter for varying the bias on said triodes at a rate whereby one of said triodes conducts upon the application of one of the input signals and the other of said triodes conducts upon the application of the other of the input signals, a pair of energy storage networks individually coupled between the plates of each of said triodes and said common terminal, each of said networks being chargeable to an energy level corresponding to the peak value of the input signal to which its associated triode is rendered conductive, a second fixed bias source having one terminal connected to said common terminal, a second transformer the primary winding of which is connected between said common terminal and said source, a pair of pentodes the respective cathodes of which are connected to said common terminal and the respective control grids of which are con-

nected to one end of the primary winding of said second transformer, the other end of the primary winding being connected to the other terminal of said second source, the respective suppressor grids being individually coupled to one of said energy storage networks, and an output transformer connected between the plates of said pentodes for differentially combining the signals developed on the plates of said pentodes in response to the energy in said networks.

8. A circuit for developing an output signal correlative to the sum of a pair of sequential alternating current input signals comprising an input terminal to which the pair of input signals are applied, a common terminal, a pair of capacitors, a pair of triodes the respective cathodes of which are connected to said common terminal and the respective plates of which are individually coupled through one of said capacitors to said input terminal, a transformer the secondary winding of which is connected between the respective control grids of said triodes, a fixed bias source interposed between said common terminal and the center of said secondary winding, a phase shifter, an alternating current source coupled to the primary winding of said transformer through said phase shifter for varying the bias on said triodes at a rate whereby one of said triodes conducts only upon the application of one of the input signals and the other of said triodes conducts only upon the application of the other of the input signals, a pair of energy storage networks individually coupled between the plates of each of said triodes and said common terminal, each of said networks being chargeable to an energy level corresponding to the peak value of the input signal to which its associated triode is rendered conductive, a linearly operated electron tube, a circuit switching device alternately interconnecting said electron tube to one of said networks at a rate controlled by said alternating current source for impressing upon the control grid of said electron tube rectangular pulses correlative to the charge on said networks, said electron tube thereby developing an output rectangular pulse having an amplitude proportional to the difference between the absolute values of the pulses applied thereto, a differentiating network connected to said electron tube for selectively differentiating the output rectangular pulses thereof, said differentiating network having a time constant characteristic small compared with the half period of said output rectangular pulse, and circuit means for amplifying the differentiated pulses.

9. A circuit according to claim 8 wherein said circuit switching device comprises a vibrator.

10. A circuit according to claim 9 and including a condenser connected across said vibrator for suppressing certain transient phenomenon therein.

11. A direction finder comprising an antenna system including four independent aerials each of which is physically positioned at the apex of a square and adapted to simultaneously derive a potential signal having a phase correlative to the bearing of an incoming electromagnetic wave relative to the respective aerial, circuit means for developing two output signals each of which results from the differential combination of the potential signals derived by each pair of diagonally positioned aerials, circuit means for developing a resultant signal correlative to the sum of all of said derived potential signals and for superimposing said resultant signal upon each of said two output signals, circuit means for sequentially amplifying and separating each of said two output signals subsequent to the superimposition of said resultant signal thereon at a predetermined sequential rate, circuit means for developing a pair of individual unidirectional signals each of which is proportional to the peak value of a respective one of said two output signals, circuit means individual to each of said last recited circuit means for developing rectangular pulses having an amplitude proportional to the difference between the absolute values of successive signals in each of said pair of unidirectional signals, circuit means individual to each of said last recited circuit means for developing a differentiated signal from each of the developed rectangular pulses, a cathode ray oscilloscope, circuit means individually intercoupling the horizontal and vertical deflection circuits of said oscilloscope to one of said last recited circuit means for applying the differentiated signal to said deflection circuits thereby to develop a linear trace on the screen thereof, said trace having a gradually decreasing thickness, and circuit means for impressing upon the intensity control grid of said oscilloscope a unidirectional rectangular pulse for blanking a portion of said linear trace.
